A. C. Carey

Carpet Sweeper

No 21815.

Patented Oct. 19, 1858.

UNITED STATES PATENT OFFICE.

AUGUSTUS C. CAREY, OF IPSWICH, MASSACHUSETTS.

CARPET-SWEEPER.

Specification of Letters Patent No. 21,815, dated October 19, 1858.

To all whom it may concern:

Be it known that I, AUGUSTUS C. CAREY, of Ipswich, in the county of Essex and State of Massachusetts, have invented certain new and useful Improvements in Carpet-Sweeping Machines, of which the following is a full, clear, and exact description, reference being had to the accompanying drawings, making part of this specification, 10 in which—

Figure 1 is a view of my improved carpet sweeper. Fig. 2 a longitudinal vertical section through the same. Fig. 3 detail to be referred to.

I am aware that a revolving brush driven by the carrying wheels of the machine has been used for a street sweeping machine and also that such a brush has been used in connection with a suitable receptacle 15 for the dust, as a carpet sweeper; the box containing the brush and dust receiver, being pushed over the carpet to collect the dust. But there are certain requisites in a carpet sweeping machine which I believe 20 have not been heretofore attained. Some of the most important of these are; that it shall sweep up close to the mop-board at the sides of the room; that the box may be thrust into corners, and out of the way 25 places (as around the fire-place, and behind articles of furniture), and the brush be there operated by hand, when it would not be convenient to obtain the required revolutions of the brush by pushing along the 30 box; and that the machine shall be cheap and durable, and not liable to be clogged by threads and similar things, which it collects in passing over the carpet. These desired ends have been obtained in my im- 35 proved carpet sweeper, which I will now proceed to describe in such a manner that others skilled in the art may understand and use my invention.

In the drawings A is the box in suitable 40 bearings in the sides of which run the journals of a wooden roll B which extend across the inside of the box. A swiveling roll or 45 caster C is placed at the back end of the box; this caster and the roll B support the box 50 as it is pushed along over the carpet by the handle D attached to the top of the box. A standard E rising from the top of the box, 55 carries a double pulley, the smaller portion a of which carries in its groove a cord b which also rests in a groove (dotted in Fig. 2) in the roll B; the larger portion d of the

pulley carries in its groove another cord c which rests in a groove e in the brush shaft F. The portion d of the double pulley has attached to it a handle f by means of which it may be turned by hand. The dust pan G (in section Fig. 2) occupies a portion of the box A in front of the roll B; it is made of sheet tin and consists of a bottom g, the front edge of which at 4 rests on the carpet when the machine is being pushed along, a back h which extends up to the top of the box A, and two side pieces i which press out against the inner sides of the box A and prevent the dust from passing out of the dust pan. The bottom g is furnished with a strip 5 soldered to the bottom near its front edge, this strip extends across the front part of the bottom g, and is inclined backward at an angle to the bottom as 70 shown in Fig. 2. It prevents the dirt which has been swept by the revolving brush up over the edge of the dust pan, from again falling out, and the dust is collected and heaped up in the pan as the sweeping proceeds.

The bottom g is turned up as shown at 6 (Fig. 1), this part lapping over the sides of the box A; this however would render the bottom too stiff, and prevent the front edge of it from springing up and down and pressing on the carpet, to prevent this undue rigidity of the bottom g the sides 6 are cut down, as seen at 7 (Fig. 1).

The pan G is held in place in the box A by spring staples m, one on each side, in the lower edge of the sides of the box. The wooden sides of the box A, each terminates at the front in a piece of sheet metal l, which is joined on to the wooden side at 8; 90 this allows the brush to be brought out nearer to the line of the outside of the side of the box than could be done if the thick wooden side of the box were continued out to the front.

The brush shaft F is supported in the following manner: To each side of the box A at g is pivoted a metal arm H which has at its outer end a pin n (dotted in Fig. 1) that passes through a slot in the piece l and enters the end of the shaft F; a screw 10 passing through a slot o in the arm H secures the arm in position. This arrangement allows the brush shaft F to be lowered as the brush is worn away by use. As each row 110 of bristles p in the brush is made continuous for the whole length of the shaft F the

cord *c* as it revolves the brush would be liable to press down the bristles into the groove *e*; to prevent this I employ a guard *I* (Fig. 3) of bent metal which is attached 5 to the inside of the top of the box *A* near the hole through which the cord *c* passes; it is so formed and placed with respect to the groove *e*, that its sides, which flare out on each side of the path of the cord *c* serve to 10 deflect the bristles as the brush revolves, until they have passed the cord *c*, when they again close in and form a continuous line. An extra bunch of bristles *r* is inserted between each row *p*, at the ends of the shaft 15 *F*; these revolve in close contact with the piece *l* on each side of the box—so that as the box is pushed along near the sides of the room the carpet may be swept close up to the mop-board.

20 This machine is operated as follows: It is pushed in the direction of its arrow, over the carpet to be swept, by the handle *D*, and as the brush is revolved rapidly (in the direction of its arrow Fig. 2) in contact with the carpet, the dust is brushed up over the front edge 4 of the dust pan *G* and is collected in it. The dust pan may be afterward removed by simply slipping it out from the staples *m* and the dust be removed 25 from it.

30 When it is required to sweep around heavy furniture, or in out of the way places where it is not convenient to give the brush the required speed by pushing the box *A* along, the brush may be operated independently of the movement of the box, by slipping the cord *b* off from the pulley *a*, and 35

revolving the brush with the required speed by means of the handle *f*; the position of the brush at the extreme front of the box *A* 40 enabling the person operating the machine to sweep out any place that is large enough to admit the front end of the box.

By making the bearings of the shaft *F* adjustable as before stated, the brush may 45 be used until the bristles or other articles of which the brush may be made are worn down so short as to be useless.

By dispensing with all cog wheels I avoid a considerable portion of the noise and rattle of the machinery when in operation, and also thereby considerably reduce the cost of 50 its manufacture.

What I claim as my invention and desire 55 to secure by Letters Patent is—

1. Placing the revolving brush at the extreme front of the box *A*, and hanging it in adjustable bearings *H* in the manner substantially as set forth.

2. I claim the deflector *I* operating substantially as described for the purpose specified.

3. I claim the combination of the revolving brush, the double pulley *a*—*b*, or its equivalent, and the roll *B* when so arranged 60 that the brush may be disconnected from the roll *B*, and be operated by hand, substantially in the manner and for the purpose specified.

AUGUSTUS C. CAREY.
